UNITED STATES PATENT OFFICE

WILLIAM E. MOORE, OF PITTSBURGH, PENNSYLVANIA, ASSIGNOR TO PITTSBURGH
RESEARCH CORPORATION, OF PITTSBURGH, PENNSYLVANIA
ELECTRIC FURNACE AND RESISTANCE ELEMENT THEREFOR

Application filed October 19, 1931. Serial No. 569,796.

My invention relates to improvements in furnace hood is provided with an interior electric furnaces, and more particularly to a furnace for heat treatment of metals, although not necessarily restricted to this use. 5
Heretofore in the operation of furnaces of this character, repairing of the furnace or of the resistance elements therein necessitate a considerable loss of time due to the fact that the furnace must cool down before 10 workmen can enter it to make repairs. I propose to overcome this difficulty by providing a resistance element which may be removed with the roof of the furnace, thereby effecting a saving in the time required 15 for repairing the furnace and resistance elements.

Another object of my invention is to provide a novel resistance element and novel supporting means therefor.

20 Other objects and advantages of my invention will be apparent during the course of the following description.

In the accompanying drawings which form a part of this specification and wherein like 25 characters of reference denote like parts throughout the same,

Figure 1 is a vertical transverse sectional view through a furnace embodying my invention.

20 Figure 2 is a longitudinal sectional view therethrough,

Figure 3 is a fragmentary horizontal sectional view showing one form of resistance element;

35 Figure 4 is a similar view showing another form of resistance element;

Figure 5 is a detail elevation of a further form of resistance element,

Figure 6 is a similar view of still another 40 form of resistance element, and,

Figure 7 is a detail of a still further form of resistance element.

In the drawings, wherein for the purpose of illustration is shown a preferred embodiment of my invention, the numeral 10 designates a heat treating furnace hood arranged over the stationary base 11. The hood 10 is provided with a removable roof 12, and the entire hood is lifted on and off the base 50 by means of the usual shop crane. The usual

which extends towards the furnace base. This shoulder collects scale, dust and dirt, and therefore must be cleaned at regular intervals. In order to obviate this difficulty I have provided the shelf 13 with a substantial slope towards its inner edge as seen in Figures 1 and 2. With this arrangement debris will slide off the shelf when the hood is raised, thereby rendering the shelf self cleaning.

In the usual furnace of this type the electric heating elements are supported on and secured to the side walls of the furnace hood. 65 In my invention the electric heating elements are supported entirely by the removable roof 12 and are removed therewith when the roof is lifted from the hood 10.

A series of heat resistant metal rods 14 carry stirrups 15 at their lower ends, and project upwardly through bushed openings in the brickwork of the roof arch, pass through bearing plates 16 and are held in the bearing plates by nuts 17 engaging the 75 screw threaded ends of the rods. Each of the stirrups 15 carries an insulating, resistor supporting spool 18. The resistor comprises a strip or ribbon 19 which passes over the spools 18 and depends therefrom in a series 80 of loops which are spaced from the walls of the hood 10 and extend to a point adjacent the shelf 13. The ends of the resistor elements are connected to terminals 20 which are arranged exteriorly of the roof and extend through the same. Various distributions of the resistor may be effected by lengthening some of the rods 14 and thereby shortening the corresponding resistor loop, as seen 85 in Figure 2.

The lower ends of the resistor loops are preferably arranged in the same plane, and are prevented from contacting with each other, and from swinging out into the furnace chamber, by refractory T-headed bolts 95 21 secured in the walls of the furnace hood and arranged between adjacent loops to serve as guides therefor, as seen in Figures 2, 3, and 4. When the roof is lifted from the furnace 100 the resistor is removed therewith, and when

a different vertical distribution of the resistor loops is desired, it is only necessary to change some of the rods 14, in contrast to the old method which required tearing down the walls of the furnace to replace the resistor supports.

5 Due to the fact that the rods 14 are in tension, they may have a small cross section, and the heat conductivity from the interior of the 10 furnace through the roof arch will consequently be reduced to a minimum. When the roof with its resistor loops is lowered onto the furnace hood, the loops are guided into position by the T-headed bolts 21.

15 While the usual flat ribbon resistor may be used, I prefer to use a resistor strip or ribbon which has been passed through a corrugating roll or the like and has a dished or channeled cross section, as seen in Figure 3.

20 This shape of heater element has greater strength than a flat ribbon due to the lateral stiffness imparted by the dishing feature, and at a very slight increase in cost. Where the dished ribbon passes over the spools 15 it 25 has a tendency to flatten out.

25 In place of the dished form shown in Figure 3, the resistor element may be passed through corrugating rolls which will give it an S-shaped cross section, as shown in Figure 4.

30 In Figure 5 I have shown another modification of the resistance element in which it is twisted into an auger shape to form a resistor which will equally expose its surface 35 to the furnace interior.

35 In Figure 6 the flat resistance element is wound into a helix of a relatively small diameter to increase the effective heating surface of the resistor.

40 In Figure 7 the resistor 19 is bent into alternate loops 22 longitudinally and transversely of the resistor strip to strengthen the resistor and to increase the exposed heating surface by its doubled corrugated effect.

45 While I have shown and described the preferred embodiment of my invention it is to be understood that various changes in the size, shape and arrangement of parts may be resorted to without departing from the spirit 50 of my invention or the scope of the subjoined claims.

Having thus described my invention, what I claim and desire to protect by Letters Patent is:

55 1. In a heat treating furnace, a base, a removable hood adapted to be placed over said base, electric heating elements arranged in proximity to the walls of said hood, and a sloping shelf arranged about the interior of 60 the hood beneath the heating elements.

2. In a heat treating furnace, a furnace hood, a removable roof therefor, a resistance element supported by said roof and adapted to extend a substantial distance down into 65 said furnace hood, and guide members se-

cured to said furnace hood for said resistance element, whereby the resistance element may be removed from the hood with said roof.

3. In a heat treating furnace, a furnace hood, a removable roof therefor, an electric resistance element supported by said roof and extending down into said furnace hood in proximity to the walls thereof, and guide supports for said resistance element arranged on the walls of the furnace hood, whereby 75 said resistance element is removable with said roof.

4. In a heat treating furnace, a furnace body, a removable roof therefor, resistance supports secured to said roof, an electric resistance element carried by said supports and extending down into said furnace body, and guide members for said resistance element secured to the walls of the furnace body.

5. In a heat treating furnace, a furnace body, a removable roof therefor, a resistance ribbon for said furnace, and means carried by said roof to support said ribbon in loops of different lengths which extend down into 85 said furnace body.

6. In a heat treating furnace, a furnace body, a removable roof therefor, a plurality of resistance supporting members depending from said roof, and means at the ends of said members for supporting a depending resistance element which extends down into the furnace.

7. In a heat treating furnace, a furnace hood, a removable roof therefor, a plurality of refractory spools supported by said roof, 100 and a depending resistance element supported on said spools and extending down into the furnace hood.

8. In a heat treating furnace, a furnace body, a removable roof therefor, a plurality of resistance supporting members depending from said roof, said members being of varying length, means at the ends of said members for supporting a resistance element which extends down into the furnace, and 110 means on the walls of the furnace body for guiding the lower end of the resistance element.

9. In a heat treating furnace, a furnace hood, a removable roof therefor, a plurality of resistance supporting elements depending from said roof, insulating spools carried by the ends of said supporting elements, a resistance strip supported by said spools and depending therefrom in spaced loops which 120 extend down into the furnace hood, means in said furnace hood for guiding the loops of resistance, and terminal members in said roof for the resistance strip.

10. In a heat treating furnace, a furnace hood, a removable roof therefor, a plurality of supporting elements of varying lengths depending from said roof, insulating spools carried by the ends of said supporting elements, a resistance strip supported on said 130

spools and depending therefrom in spaced loops of various lengths which extend down into the furnace hood.

11. In a heat treating furnace, an electric resistance element comprising a strip of resistance material twisted into an auger shape, the overall width of which is substantially equal to the width of the strip from which the auger shaped element is formed.

10 12. In a heat treating furnace, an elec-

tric resistance element comprising a strip of resistance material twisted into an auger shape and arranged in a series of spaced loops in the furnace, the overall width of the auger shaped element being substantially equal to the width of the strip from which it is formed.

In testimony whereof I affix my signature.
